UNITED STATES PATENT OFFICE.

WILLIAM H. MEYER, OF ST. LOUIS, MISSOURI, ASSIGNOR TO BLUE BIRD MANUFACTURING COMPANY, OF ST. LOUIS, MISSOURI, A CORPORATION OF DELAWARE.

DESIGN FOR A WASHING-MACHINE CASE.

54,441.

Specification for Design.

Patented Feb. 10, 1920.

Application filed July 3, 1919. Serial No. 308,677. Term of patent 14 years.

To all whom it may concern:

Be it known that I, WILLIAM H. MEYER, a citizen of the United States of America, residing in St. Louis, in the State of Missouri, have invented a new, original, and ornamental Design for a Washing-Machine Case, of which the following is a specification, reference being had to the accompanying drawing, forming a part thereof.

The drawing is a perspective of a washing machine case showing my new design.

I claim:

The ornamental design for a washing machine case substantially as shown.

In testimony that I claim the foregoing I hereunto affix my signature.

WILLIAM H. MEYER.
